United States Patent Office

Des. 182,478

Patented Apr. 8, 1958

182,478

PORTABLE CAFETERIA COUNTER

Delmar D. Rhoads, Fort Wayne, Ind.

Application January 15, 1957, Serial No. 44,504

Term of patent 14 years

(Cl. D14—3)

Fig. 1 is a perspective view of a portable cafeteria counter showing my new design; and

Fig. 2 is a front perspective view thereof.

The back of the cafeteria counter is substantially plain.

I claim:

The ornamental design for a portable cafeteria counter, as shown and described.
